(57) **CLAIM**

The ornamental design for a beaded sliding valve handle, as shown and described.

DESCRIPTION

FIG. 1 is a perspective view of a beaded sliding valve handle, showing my new design in an upright closed position;

FIG. 2 is a rear elevational view thereof;

FIG. 3 is a front elevational view thereof;

FIG. 4 is a left side elevational view thereof, the right side being a mirror image thereof;

FIG. 5 is a left side elevational view thereof, shown in a tilted open position;

FIG. 6 is a top plan view, shown in an upright closed position; and,

FIG. 7 is a bottom view thereof.
